UNITED STATES PATENT OFFICE.

GEORGE BONENBERGER AND JAMES R. GOODWIN, OF EVANSVILLE, INDIANA,
ASSIGNORS TO STEEL SCAFFOLDING COMPANY, OF EVANSVILLE, INDIANA,
A CORPORATION OF INDIANA.

FOLDING BRACKET-SCAFFOLD.

1,125,051.

Specification of Letters Patent. Patented Jan. 19, 1915.

Application filed April 28, 1913. Serial No. 764,682.

To all whom it may concern:

Be it known that we, GEORGE BONENBERGER and JAMES R. GOODWIN, citizens of the United States, residing at Evansville, 5 county of Vanderburg, and State of Indiana, have invented certain new and useful Improvements in Folding Bracket-Scaffolds, of which the following is a specification.

10 This invention relates to folding bracket scaffolds.

Our object is to provide a light, strong, durable and inexpensive bracket scaffold of improved construction having a novel combination of adjustable and foldable supporting bar, supporting braces, and tie or hanger, whereby the scaffold may be readily applied to the outside of a building and engaged with the studding thereof enabling 20 carpenters to place any suitable support such as planks on a plurality of the brackets and to work on the outside of a building.

The invention consists of an improved bracket scaffold comprising a supporting bar, two foldable supporting braces, and a tie or hanger combined in a new and improved manner as will more fully appear hereinafter.

In the accompanying drawings:—Figure 30 1 is a perspective of the invention applied to the side of a building, and representing a plank broken away, supported thereby; Fig. 2, a plan view of the bracket when folded; and Fig. 3, an edge view thereof.

35 The bracket scaffold has a bar support 1 provided with an upwardly projecting retainer 2 at its outer end to prevent the plank or other platform from accidentally slipping from the support. At its inner end 40 the supporting bar 1 has a square hook 3 adapting it to engage a piece of studding in the building on which the bracket is used.

The main supporting braces 4 and 5 are pivoted at 6 to the outer end part of the 45 supporting bar 1 by a rivet or bolt, and they are provided with bent feet 7 which may have openings to receive nails driven into the building, if desired, or, these feet need have no openings of any kind and simply 50 abut the building, as the use of nails or fasteners is not necessary. The supporting braces 4 and 5 are preferably of angle iron construction for the sake of strength. The supporting braces are connected rigidly by

a cross-piece 8 which keeps them relatively 55 widely separated at their lower parts, affording a wide bearing on the side of the building. This prevents any lateral movement of the scaffold.

A tie or hanger 9 has bent ends 10 received in holes in the braces 4 and 5, said ends being headed or flattened or otherwise provided with means to prevent them from coming out of the said holes, but at the same time without interfering with the 65 pivotal connection thus provided between the braces 4, 5 and 9. Preferably, the tie or hanger 9 is made of a single piece of bent rod and the apex 11 is sufficiently broad to permit it to slide readily on the bar 1 when 70 adjusting the bracket or when folding or extending it, while at the same time preventing cracking or breaking at the bend 11. The tie or hanger 9 transmits directly to the supporting braces 4 and 5 any weight 75 imposed upon either side of the supporting bar 1, thus preventing any twisting motion which would result in the "walking" of the feet 7 on the wall of the building.

The scaffold is shown in position for use 80 in Fig. 1 and in folded condition in Figs. 2 and 3. Being adapted for folding substantially flat, as shown in Figs. 2 and 3, a number of scaffold brackets may be packed into very compact form for shipping purposes and they can be readily separated and opened out at the point of use.

The bar 1, main braces 4, 5, and tie or hanger 9 can be adjusted in relation to each other, according to the position of the 90 bracket on the building, so as to locate the plank supporting bar 1 as may be desired by the carpenter or other artisan. The combination of the bar 1, the main and supporting braces 4, 5, and tie or hanger 9 affords 95 great rigidity and strength.

Having thus described our invention, what we claim as new and desire to secure by Letters Patent, is:—

An all-metal foldable bracket scaffold 100 comprising the combination of a single supporting bar having a hook at its inner end adapted to engage the building, a main supporting brace composed of connected members converging and pivoted to the outer 105 part of the supporting bar and foldable in relation to said supporting bar alongside the latter, the other ends of the supporting

members being adapted to rest against the building, and a one-piece inverted V-shaped tie or hanger whose apex straddles, rests upon, and is slidable and foldable on, the 5 supporting bar and whose end parts are pivoted to the free end parts of the respective members constituting the main supporting brace, in such a way that when weight is imposed on one side of the 10 supporting bar such weight is transmitted di-

rectly to the inner end of the supporting brace on that side of the bar, thus preventing all twisting motion.

In testimony whereof, we hereunto affix our signatures in presence of two witnesses. 15
